J. G. WEIR

HYDRAULIC INSTALLATION

Filed Feb. 2, 1924

INVENTOR.
James George Weir.

By William C. Slaton
Atty.

UNITED STATES PATENT OFFICE.

JAMES GEORGE WEIR, OF CATHCART, GLASGOW, SCOTLAND, ASSIGNOR TO G. & J. WEIR, LIMITED, OF GLASGOW, SCOTLAND.

HYDRAULIC INSTALLATION.

Application filed February 2, 1924. Serial No. 690,238.

To all whom it may concern:

Be it known that I, JAMES GEORGE WEIR, a subject of the King of Great Britain, and residing at Cathcart, Glasgow, Scotland,

5 have invented certain new and useful Improvements in Hydraulic Installations; and I do hereby declare the following to be a full, clear, and exact description of the invention, such as will enable others skilled in 10 the art to which it appertains to make and use the same, reference being had to the accompanying drawing, and to letters or figures of reference marked thereon, which form a part of this specification.

15 This invention relates to hydraulic installations and comprises improved means for supplying and maintaining fluid at a desired pressure in a main service pipe and the like where the use of an accumulator is 20 inadmissible. In such cases the use of centrifugal pumps also has heretofore been inadmissible or very objectionable owing to the very high expenditure of energy involved in continuously running the centrifugal 25 pump at the speed necessary to generate the required pressure. Displacement pumps are therefore commonly employed: such pumps are—especially in the case of large installations—objectionably heavy, costly, and expensive in upkeep.

30 By displacement pumps are meant pumps in which the fluid is pumped by being pressed out of a space (for example a cylinder) by a piston or its equivalent, as distinct 35 from pumps of the centrifugal and turbine type.

The object of the present invention is to 40 permit of the employment for this service of a centrifugal pump of a light and compact construction so that the advantages of this type of pump may be obtained without the disadvantages of high power consumption at low loads. This object is attained by the provision of a small auxiliary or secondary 45 pump, preferably of the displacement type, capable of supplying the amount of pressure fluid required to make up leakages and small demands upon the main service pipe or the like and operating in conjunction or 50 combination with a relatively large main

pump of the centrifugal type capable of performing the full duty or meeting the maximum demands upon the main service pipe.

The main pump is connected to the main 55 service pipe or the like so that it supplies pressure fluid thereto through a non-return valve.

The auxiliary or secondary pump is also connected up to supply pressure fluid to the 60 main service pipe or the like. This pump is of small capacity, but it is capable of supplying the amount of fluid required to make up leakages and for small demands upon the main service pipe. 65

A governor is provided which controls the supply of actuating fluid to the motor which drives the main pump, the arrangement being such that, as long as the pressure in the main service pipe exceeds a certain 70 minimum pressure, actuating fluid is supplied to the said motor in amount only sufficient to maintain the pump continuously running at a relatively low speed—such a 75 speed that the delivery pressure of the pump is substantially lower than the working pressure in the main service pipe.

Under such conditions—which exist at standby or at low load—the auxiliary pump acts to maintain the working pressure in 80 the main service pipe while the main pump—running at a low speed—consumes an amount of power small compared with what it would absorb were it required to deliver at the service pipe pressure. 85

When, however, a demand is made on the main service pipe for more fluid than the auxiliary pump can supply, and when consequently the pressure in the main service pipe falls below a certain predetermined 90 value, the governor permits the main pump to receive sufficient actuating fluid to enable it to come into useful operation and deliver at the requisite pressure to maintain the required working pressure in the main 95 service pipe.

The present invention—which will be defined in the annexed claims—will now be more particularly described with reference to the accompanying drawing which illus- 100

trates the carrying of the invention into effect in one convenient manner as applied to gun-moving gear for warships.

5 h is the main service pipe. a is the main pump—of the centrifugal type: it is driven by the steam turbine b : it delivers into the main service pipe through the non-return valve v and the pipe o . c is the auxiliary pump: it is a small displacement pump—
10 steam-driven: it discharges into the main service pipe by way of the pipe n . e is the pipe which supplies steam to the two pumps. t is a tank from which the two pumps—by the pipes s and r respectively—
15 draw their fluid (for pressure supply).

20 A governor m is arranged on the steam-supply pipe e . It is controlled by the pressure in the main service pipe h in such a manner that steam is shut off from the turbine b as long as the pressure in the main service pipe exceeds a certain minimum pressure.

25 A certain amount of steam is however—by the pipe k —allowed to by-pass the governor-operated steam valve of the turbine b , and the governor is so adjusted that this by-pass steam is sufficient in quantity to maintain the pump continuously running at a low speed: at this speed the delivery 30 pressure of the pump is substantially lower than the working pressure in the main service pipe.

35 In working at standby or at low load conditions, the small displacement pump c is able to maintain the working pressure in the main service pipe; and the steam valve on the steam pipe to the turbine b is shut by the action of the governor. The main pump is rotating at a low speed by 40 means of the by-pass steam, and is accordingly not consuming the large amount of power which it would require were it running to maintain the full pressure. Immediately a demand is made on the main service pipe for more fluid than the displacement pump can supply, the pressure falls in the pipe, and the main pump is 45 given full steam by the governor and comes into useful operation.

50 The arrangement just described is for steam-driven pumps; but electrically driven pumps—both main and auxiliary—may be used, if desired, and controlled by suitable devices to operate in a similar manner.

55 Having thus described my invention, what I claim as new and desire to secure by Letters Patent is:—

1. The combination with a main hydraulic service pipe of a main pump of the centrifugal type capable of maintaining the required working pressure in the said pipe under full demands for fluid, an auxiliary pump which is relatively small compared with the said main pump and which is 60 capable of maintaining the required work-
65

70 ing pressure in the said pipe against small leakages and small demands for fluid, a governor controlled by the pressure in the said pipe, means whereby the said governor controls the said main pump according to the pressure in the said pipe, together with means, out of the control of said governor, whereby the main pump is run at a low speed when only small demands are being made on the said pipe. 75

2. The combination with a main hydraulic service pipe of a main pump of the centrifugal type capable of maintaining the required working pressure in the said pipe under full demands for fluid, a steam motor driving the said pump, an auxiliary pump which is relatively small compared with the said main pump and which is capable of maintaining the required working pressure in the said pipe against small leakages and small demands for fluid, a steam motor driving the said auxiliary pump, means for supplying steam to the said motors, a governor controlled by the pressure in the said pipe, means whereby the said governor controls the supply of steam to the said main pump according to the pressure in the said pipe, and a by-pass, out of the control of said governor, whereby steam is passed to said motor in sufficient amount to keep said main pump running at a low speed when only small demands are being made on said pipe. 85

3. The combination with a main hydraulic service pipe of a main pump of the centrifugal type capable of maintaining the required working pressure in the said pipe under full demands for fluid, an auxiliary pump of the displacement type which is relatively small compared with the said main pump and which is capable of maintaining the required working pressure in the said pipe against small leakages and small demands for fluid, a governor controlled by the pressure in the said pipe, means whereby the said governor controls the said main pump according to the pressure in the said pipe, together with means, out of the control of said governor, whereby the main pump is run at a low speed when only small demands are being made on the said pipe. 90 100 105 110 115

4. The combination with a main hydraulic service pipe of a main pump of the centrifugal type capable of maintaining the required working pressure in the said pipe under full demands for fluid, a steam motor driving the said pump, an auxiliary pump of the displacement type which is relatively small compared with the said main pump and which is capable of maintaining the required working pressure in the said pipe against small leakages and small demands for fluid, a steam motor driving the said auxiliary pump, means for supplying steam 120 125 130

to the said motors, a governor controlled by the pressure in the said pipe, means whereby the said governor controls the supply of steam to the said main pump according to the pressure in the said pipe, and a bypass, out of the control of said governor, whereby steam is passed to said motor in sufficient amount to keep said main pump running at a low speed when only small demands are being made on said pipe. I hereby sign my name to this specification.

10

JAMES GEORGE WEIR.
